VALVE MECHANISM

Eugene Martin, Erie, Pa., assignor to The Standard Stoker Company, Incorporated, a corporation of Delaware

Application February 25, 1942, Serial No. 432,275

3 Claims. (Cl. 251—145)

This invention relates to stokers actuated by a fluid pressure motor, but more particularly to a valve for controlling the supply of pressure fluid to the motor for the stoker.

An object of the invention is to provide a valve capable of adjustment to deliver fluid to a fluid actuated motor at a predetermined pressure below that of the source of supply and that can be manipulated to quickly deliver fluid to the motor at a higher pressure, up to the pressure of the source of supply, if desired.

A further object of the invention is to provide a valve of the type described above that is automatically and instantaneously returnable to its originally adjusted position after having been manipulated to deliver fluid to the motor at a pressure above that for which it was originally set.

A further object of the invention is to provide in a unitary structure, a valve of the type described, that is positive and reliable in its action, consists of relatively few, simply constructed parts, and that can be manufactured at comparatively small cost.

In a stoker installation wherein the fuel conveying mechanism is operated by a pressure fluid actuated motor, it is conventional to interpose an operating valve in the pressure fluid line between the source of pressure fluid supply and the motor, which valve is adjustable to deliver fluid to the motor at a pressure below that of the source of supply and at which the stoker normally operates. For various reasons, the stoker fuel conveying mechanism may at times stall at the normal engine operating pressure, for example, when the conveying mechanism becomes overloaded or choked. At such times it is desirable quickly and sharply to increase the fluid pressure to the stoker engine in order to effect resumption of operation of the conveying mechanism without delay, and when the choked condition has been relieved, to instantaneously reduce the fluid pressure to the stoker engine to that required under normal operating conditions.

It is, therefore, another object of the invention to provide an operating valve for a stoker engine arranged for adjustment to deliver fluid to the stoker engine at a predetermined pressure below that of the source of supply, the operating valve having combined therewith a quick action booster arrangement for sharply increasing the fluid pressure to the stoker engine and being instantaneously returnable to the originally adjusted position under the control of the operator.

With the above and other objects in view, the invention consists in the improved construction, combination and relative arrangement of the several parts as hereinafter more fully described, claimed and illustrated in the accompanying drawings, and wherein

Fig. 1 is a fragmentary view of the rearward portion of a locomotive with a stoker, stoker engine and the novel valve applied thereto, all being shown in side elevation;

Fig. 2 is a view of the novel valve, shown partly in elevation and partly in vertical central section;

Fig. 3 is a sectional view taken on the line 3—3 of Fig. 2; and

Fig. 4 is a sectional view taken on the irregular line 4—4.

As a preferred embodiment, the invention is illustrated in the drawings and will be described as applied to the stoker engine of a locomotive, but it will be apparent that the novel valve mechanism is equally adaptable to engines for operating other devices and appliances.

Referring specifically to Fig. 1, the locomotive is indicated by the letter L and comprises a frame 10 upon which the boiler 11 is supported by means of an expansion plate 12. A cab deck 13 extends rearwardly from the boiler 11 and is supported at its rearward end on the frame 10 by expansion plate 14.

The stoker is shown at S and includes a fuel discharge conduit 15 supported at its upper end from the backhead of the boiler 11 by a bracket 16 and at its lower end by a bracket 17. The lower end of the discharge conduit 15 is flexibly connected with and supports the forward end of another conduit 18 leading forwardly from the tender (not shown). A conveyor screw, such as 19, extends through the conduits 15 and 18 and conveys fuel therethrough for delivery into a firebox with which the boiler 11 is provided. The conveyor screw 19 is operated by means of gearing (not shown) driven by shafting 20 having an operative connection with the stoker engine E.

The engine E is of the multi-cylinder, double acting type and utilizes steam or other pressure fluid as an operating medium therefor. The engine is rigidly secured to the locomotive frame 10 in any suitable manner. Steam from the locomotive boiler is conducted to the stoker engine E through the pipe 21.

In practice the stoker engine normally operates the stoker at a pressure below boiler pressure, so that an operating valve is interposed in

the steam pipe between the source of steam supply and the engine, which valve may be regulated to control the steam pressure to the engine. As an illustration, the locomotive boiler pressure may be 250 pounds per square inch while the stoker engine may operate normally at 25 pounds per square inch.

At times, however, the stoker engine will stall, for example, when the stoker conveyor becomes overloaded or choked. When this occurs, it is desirable to deliver to the stoker engine a sudden charge of steam at boiler pressure, whereupon in most instances the stoker engine will resume operation and the overload or clog in the stoker conveyor will be relieved. As soon as the overload or clog is relieved it is desirable to instantaneously reduce the steam pressure to the stoker engine to its original normal setting to prevent the stoker engine from racing.

There will now be described a simple and efficient combined operating and booster valve that is interposed in the steam line between the source of supply and the stoker engine and that accomplishes the above desired results. The novel combined operating and booster valve is shown at 22 in Fig. 1.

Referring now to Figs. 2, 3 and 4 showing the details of construction of the novel combined operating and booster valve 22, the valve 22 comprises a valve body 23 having a valve seat 24 dividing the valve body into chambers 25 and 26. The valve seat 24 is provided with a valve opening 27 which connects the chambers 25 and 26 with one another when the valve 22 is open. The valve body 23 is provided with an inlet 28 through which steam passes from the locomotive boiler to the chamber 25, and an outlet 29 through which steam passes from the chamber 26 to the stoker engine E.

Threaded in the valve seat 24 is a seat ring 30 arranged to receive the lower disc portion 31 of the valve stem 32, the disc 31 and stem 32 being secured together by disc stem ring 33. The disc 31 is received in the bonnet 34 which is secured to the valve body 23 by the union bonnet ring 35. The bonnet 34 has an integrally formed yoke 36 provided at its upper end with an externally and internally threaded collar 37, through which collar the upper end of the valve stem 32 projects.

To prevent leakage of steam between the disc 31 and the bonnet 34, the latter is provided with a stuffing box in which is received packing 38. The packing 38 is retained in the stuffing box by a gland 39 which is securely held in place by the packing nut 40, the latter being in threaded engagement with the yoke 36 of the bonnet 34.

A compressed spring 41 surrounds the yoke 36 and is held between the upper retaining ring 42 and the lower retaining ring 43. The upper retaining ring 42 is threaded on the yoke collar 37 and the lower retaining ring 43 is seated on the projecting arms 44, 45 of a support member 46 carried by the valve stem 32. The compressed spring 41 thus normally urges the disc 31 of the valve stem 32 toward the seat ring 30.

Threaded in the yoke collar 37 is a threaded bushing 47, through which bushing the free end of the valve stem 32 projects. The projecting portion of the valve stem 32 carries a hand wheel 48 which is secured against the bushing 47 by a nut 49 threaded on the free end of the valve stem 32. The valve stem 32 is provided at its upper end with a key 50 extending axially of the valve stem 32, and the bushing 47 is provided with a groove 51 arranged to receive the key

50. The hand wheel 48 is also provided with a groove (not shown) arranged to receive the key 50.

By reason of the key and groove arrangement, it will be seen that when the hand wheel 48 is turned, the valve stem 32 and bushing 47 turn along with it, whereby the bushing 47 can be threaded in and out of the collar 37, thereby moving the valve stem disc 31 into engagement or away from the seat ring 30. Also by reason of the key and groove arrangement, it will be seen that by pulling the hand wheel 48 instead of turning it, with a force sufficient to overcome the compression of the spring 41 which normally forces the disc 31 toward the valve seat 27, the disc 31 can be instantaneously moved away from the valve seat 27 to fully open the valve and provide communication between the chambers 25 and 26. Upon releasing the hand wheel 48, the compression spring 41 will then return the disc 31 to its original setting.

In operation, as stated before, the chamber 25 communicates with the locomotive boiler where, for example, the steam pressure may be 250 pounds per square inch, while the chamber 26 communicates with the stoker engine E, which normally operates at, for example, steam pressure of 25 pounds per square inch. The hand wheel 48 is, therefore, turned to move the disc 31 away from the seat ring 30 the required distance to admit steam from the chamber 25 to the chamber 26 at the pressure necessary for normal operation of the stoker engine E. The spring 41 retains the disc 31 at this setting against the pressure in the chamber 25.

Now, if the stoker conveyor should stall because of a clog or a hard lump of coal, the stoker operator grasps the hand wheel 48 and pulls it out, thereby moving the disc 31 away from its original setting and instantaneously providing a full opening at 27 to admit steam at boiler pressure to the chamber 26 and the stoker engine E. At this pressure the stoker engine will in most cases operate the stoker conveyor to relieve the clog or crush the hard lump of coal. When the stoker engine starts to race, indicating that the clog in the stoker conveyor has been relieved, the operator releases the hand wheel 48, and the spring 41 forces the disc 31 back to its original setting, thereby again admitting steam to the chamber 26 and the stoker engine E at the pressure required in normal operation.

I claim:

1. A valve comprising a casing, a seat in said casing, a bonnet mounted on the casing, a bushing threaded in the free end of said bonnet, a valve member engageable with the seat for closing the valve, said valve member projecting through said bushing, locking means between said bushing and said valve member providing for rotation of one by the other and providing for longitudinal movement of said valve member through said bushing, a handle associated with said bushing and valve member for threading said bushing in and out of said bonnet to move said valve member to any one of a number of set positions and for moving said valve member longitudinally from its set position by an application of manual force, and yieldable means for returning said valve member toward its set position upon release of said force, said handle overlapping said bushing for limiting movement of said valve member by said yieldable means to its set position.

2. A valve comprising a casing, a seat in said casing, a bonnet mounted on the casing, a bush-

ing threaded in the free end of said bonnet, a valve member engageable with the seat for closing the valve, said valve member projecting through said bushing, said bushing and said valve member being provided one with a keyway and the other with an engaging key providing for longitudinal movement of said valve member through said bushing and providing for rotation of one by the other, a common means associated with said bushing and valve member for selectively threading said bushing in and out of said bonnet for moving said valve member to any one of a number of set positions and for moving said valve member longitudinally from its set position by an application of manual force, yieldable means for returning said valve member toward its set position upon release of said force, said common means and said bushing providing stop means for limiting movement of said valve member by said yieldable means to its set position.

3. A valve comprising a casing, a seat in said

casing, a bonnet mounted on the casing, a bushing threaded in the free end of said bonnet, a valve member engageable with the seat for closing the valve, said valve member projecting through said bushing, locking means associated with said bushing and said valve member providing for rotation of one by the other and providing for longitudinal movement of said valve member through said bushing, a common means associated with 5 said bushing and valve member for selectively threading said bushing in and out of said bonnet to move said valve member to any one of a number of set positions and for moving said valve member longitudinally from its set position by an application of manual force, yieldable means for 10 returning said valve member toward its set position upon release of said force, said common means and said bushing providing stop means for limiting movement of said valve member by said yieldable means to its set position.

EUGENE MARTIN.
